UNITED STATES PATENT OFFICE.

ROBERT A. WILSON, OF CANTON, OHIO, ASSIGNOR OF TWO-THIRDS TO
H. A. CRONAH AND W. P. HALL, OF SAME PLACE.

ANNEALING-BOX.

SPECIFICATION forming part of Letters Patent No. 613,001, dated October 25, 1898.

Application filed November 26, 1897. Serial No. 659,911. (No model.)

To all whom it may concern:

Be it known that I, ROBERT A. WILSON, a citizen of the United States, residing at Canton, Ohio, have invented certain new and useful Improvements in Annealing-Boxes, of which the following is a specification.

My invention is an improved annealing-box intended to provide a construction which will be durable and successfully withstand the intense heat to which these boxes are subjected, the construction being such also as to provide for expansion and contraction of the top plate and such also as to prevent the top plate from sagging or buckling.

15 In the accompanying drawings, Figure 1 is a plan view of the annealing-box with the top removed. Fig. 2 is a side elevation with one end and a part of the top in section. Fig. 3 is a cross-section through the box and top, 20 and Fig. 4 is a detail view showing a part of one side of the box with the top plate and its supporting-ledge.

The box may be made of cast or wrought iron or steel, as may be found desirable, and 25 it comprises end sections A and side sections B. The side sections may be in two parts, and all the sections I make with interlocking tongues and recesses a and secure the sections together by suitable bolts b, connecting the 30 parts at each joint. The sides, as shown in Fig. 1, are also in section, with tongues in one section fitting in recesses a in the other sections, and bolts b' secure the sections of the sides together at these joints. In order to 35 brace the whole structure longitudinally, I extend rods c between the end plates from end to end, passing the rods through ears d, which prevent the rods from buckling under the heat and keep them straight, the ears being located at intervals on the inner wall of the side sections.

In order to support the top plate, I form a 40 ledge e around the inner wall of the sections, this ledge projecting inwardly, and at intervals the ledge is slightly extended, as shown at f, and these extended portions are provided with openings adapted to receive threaded bolts g. The top plate h is of slightly less width and length than the opening constituting the entrance to the box, so as to allow for the contraction and expansion of the

plate without buckling, and after the top has been placed upon the ledge the bolts g are passed down through elongated openings i in the top plate, these openings allowing for the 55 expansion and contraction, and covering the openings are small plates k, which form supports for the heads l, fitting on the ends of the bolts g. Instead of nuts being used for this purpose any form of fastening will do, 60 provided it keeps the top plate to its seat.

In order to prevent the buckling of the top plate under the intense heat, I stiffen the plate by ribs n, which extend, preferably, cross-wise of the top plate, as shown in Figs. 2 and 65 3, being bolted by flanges to the said plate. The ribs are preferably arched; but this is not essential.

This construction provides a very simple form of annealing-box and one which is very 70 durable by reason of the secure manner in which it is held together and the various parts thereof braced and strengthened.

The bolts which hold the sections together at the corners have their ends and nuts located in recesses x in the sections, and they 75 extend therefrom across the joint and through the other section.

It will be noticed that the ledges are arranged below the upper edge of the sides of the box, so that sand may be filled in this space above the top plate, and this sand will cover the joint about the edges of the top plate, which, it will be seen, does not reach to the sides of the box, and in this way allows 85 for expansion.

The corners of the box are inclined or filleted at G, and the edge of the top plate will rest against this incline, and the sand will rise and fall as the parts expand and contract.

In the contracting of the box the incline will allow the sand to slide upon it easily, and in expanding the sand will drop down, following the top plate, keeping the cracks 95 air-tight, but not interfering with the free expansion and contraction of both the top plate and the sides of the box.

Another advantage is that a fillet in the corner will make it stronger, and this is particularly of advantage in a cast-iron box. 100 The top plate in this box is not bolted tight,

but is left free to expand and contract without putting on the sides, so if the edge of the plate were square and the corner of the ledge were square the sand would pack in the corner and not allow the free expansion and contraction; but having the beveled corner the sand will follow the incline up and down.

What I claim is—

1. An annealing-box comprising end and side sections with interlocking tongues and recesses, bolts connecting the sections at the joints and longitudinally-extending brace-rods supported in ears on the inner walls of the side sections and passing through the end sections, substantially as described.
2. An annealing-box comprising the ends, the sides in sections, each section and end having a horizontal ledge thereon, the sections of the sides having an interlocking tongue and recess between them with transverse connecting-bolts, longitudinally-extending brace-rods for holding the sections together, and a cover fitting within the top of the box and resting on the horizontal ledges, substantially as described.
3. In combination in an annealing-box, the sides and ends having the horizontal ledges with extensions *f* at intervals, the inclined

fillet at the corner of the ledges, a top plate having elongated openings at the points corresponding to the extensions to overlie the same, the bolts extending from the extensions up through the elongated opening of the top plate and the cover-plates *k* over the elongated openings, substantially as described. 35

4. In combination, the box, the ledge below the upper edge thereof forming an upper sand-receiving space, the top plate resting on the said ledge and being of smaller size than the space between the sides of the box, the fillets in the corners of the upper space and means for holding the top plate to allow expansion and contraction, substantially as described.

5. In combination, the box having a ledge 45 below its top, with a filleted corner and a cover resting on the ledge and adapted to ride up the fillet under expansion of the parts, substantially as described.

In testimony whereof I affix my signature 50 in presence of two witnesses.

ROBERT A. WILSON.

W. H. CAVNAH.

Correction in Letters Patent No. 613,001.

It is hereby certified that the name of the first-mentioned assignee in Letters Patent No. 613,001, granted October 25, 1898, upon the application of Robert A. Wilson, of Canton, Ohio, for an improvement in "Annealing-Boxes," was erroneously written and printed "H. A. Cronah;" that said name should have been written and printed *H. A. Cavnah*; and that the said Letters Patent should be read with this correction therein that the same may conform to the record of the case in the Patent Office.

Signed, countersigned, and sealed this 1st day of November, A. D., 1898.

[SEAL.]

Countersigned:

C. H. DYE^{LL},
Commissioner of Patents.

THOS. RYAN,
First Assistant Secretary of the Interior.
